DESIGN FOR A COSTUMER

Ruth H. Nebel, Sturgeon Bay, Wis.

Application August 24, 1933. Serial No. 49,101

Term of patent 14 years

To all whom it may concern:

Be it known that I, RUTH H. NEBEL, a citizen of the United States, residing at Sturgeon Bay, in the county of Door and State of Wisconsin, have invented a new, original, and ornamental Design for Costumers, of which the following is a specification, reference being had to the accompanying drawing, forming part thereof.

Figure 1 is a view in perspective of a costumer built according to my invention as it appears in closed position, and

I claim:—

The ornamental design for a costumer, as shown and described.

In witness whereof, I hereunto subscribe my name this 11th day of August, 1933.

RUTH H. NEBEL.
